SASH CONSTRUCTION

Christian M. Verhagen, Elkhart, Ind., assignor to
The Adlake Company, Chicago, Ill., a corpora-
tion of Illinois

Application January 15, 1937, Serial No. 120,763

5 Claims. (Cl. 189—76)

The object of this invention is to provide a vertically slideable sash in which side rails of improved construction are employed. A sash with this new side rail construction is quite weather-tight, affords a large area of vision, is amply strong even in the larger sizes, is attractive in appearance, and may be manufactured at small cost.

While the foregoing statements are indicative 10 in a general way of the nature of the invention, other more specific objects and advantages will be apparent to those skilled in the art upon a full understanding of the construction, arrangement and cooperation of the parts which combine to produce the sash.

One form of the invention is presented herein for the purpose of exemplification, but it will of course be appreciated that the invention is susceptible of embodiment in other structurally 20 modified forms coming equally within the scope of the appended claims.

In the accompanying drawings:

Fig. 1 is a perspective view of one side of a sash constructed in accordance with the invention;

Fig. 2 is an edge view of the sash;

Fig. 3 is a face view of one of the upper corners of the sash;

Fig. 4 is a horizontal section, taken on the line 4—4 of Fig. 3;

Fig. 5 is a vertical section, taken on the line 5—5 of Fig. 3;

Fig. 6 is a horizontal section, taken on the line 6—6 of Fig. 3;

Fig. 7 is a face view of one of the lower corners of the sash;

Fig. 8 is a horizontal section, taken on the line 8—8 of Fig. 7; and

Fig. 9 is a vertical section, taken on the line 9—9 of Fig. 7.

As will be observed in the drawings, the sash 10 consists of a pane of glass 11 which is supported at its edges in rubber glazing strips 12 set into grooves in top, bottom and side rails 13, 14 and 15. The top and bottom rails 13 and 14 are 45 of ordinary construction, but the side rails 15 (of which only one is shown) are of special construction.

Each of the side rails 15 of the sash consists of two sheet metal channel strips 16 and 17 and 50 a pile fabric strip 18. The metal strips 16 and 17 are nested together in tightly fitting relation, with the strip 16 on the outside and the strip 17 on the inside, and the back and sides of the outer strip 16 are covered by the fabric strip 18, with 55 the edges 19 of the latter clamped between the

sides of the strip 16 and the sides of the strip 17. The strip 17 is provided adjacent the fabric covered edges of the strip 16 with outturned flanges 20 which terminate approximately flush with the pile 21 of the fabric on the sides of the rail. The 5 channel 22 which is present in the inner metal strip 17 serves as a glazing groove and is occupied by the glazing strip 12 on the vertical edge of the glass 11.

The upper and lower ends of this composite 10 rail structure are attached to the ends of the top and bottom rails 13 and 14 by means of solid metal blocks 23 and 24. These blocks are fixedly secured in the hollow ends of the top and bottom rails and project therefrom into the channel 22 15 in the inner strip 17. The projecting portions of the blocks 23 and 24 fit tightly within the channel and are detachably held in position by means of screws 25 which pass through the back of the rail into the blocks. The outturned flanges 20 20 on the edges of the inner strip 17 are drawn up against the cut ends of the top and bottom rails at 26, giving a nicely finished appearance to the joints in the corners of the sash. The metal channel strips 16 and 17 may be secured 25 together at intervals between the top and bottom rails by means of rivets 27.

The bottom rail 14 of the sash, which is shown 30 as being of thin sheet metal construction, is provided along its lower edge with a rubber sealing strip 28 which is shaped to conform to an inclined sill, and the lower end of the side rail 15 projects downwardly on the outside of the sash a short distance beyond the lower outer edge of the bottom rail 14, terminating just above the lower 35 surface of the sealing strip 28 at approximately the same angle as the latter, with the end of the sealing strip disposed within the angularly cut end of the side rail. The fabric strip 18 of the side rail preferably projects downwardly a little 40 beyond the lower edges of the metal channel strips 16 and 17 in order to provide a soft sealing fillet 29 at the outer corner.

If desired, thin sheet metal plates 30 of generally triangular shape may be positioned against 45 the outer and inner surfaces of the glass 11 at the corners of the sash, within the grooves in the glazing strips 12, in order to give a rounded effect to the corners.

The improved side rail which constitutes this 50 invention permits of a sash which is not only inexpensive to manufacture and easy to assemble but is light in weight, quite rigid and affords a large area of vision. The tightly nested association of the sheet metal channel strips 16 and 55

- 11, combined with the spread of the outturned flanges 20 on the inner strip 17, prevents any appreciable distortion of the side rails under the stresses to which sash are ordinarily subjected in service. The outturned flanges 20 also act as protective baffles for the pile 21 of the fabric strips, diverting air currents, rain and foreign particles from the sealing portions of the rails.
- 10 If desired, the rivets 27 may be omitted in order to render the metal strip 18 which carries the fabric strip 19 readily detachable from the metal strip 17, whereby to facilitate the replacement of the fabric strip.
- 15 A sash constructed in accordance with the invention is especially applicable to car and bus windows, where lightness combined with strength and rigidity are especially important factors.
- I claim:
- 20 1. In a sash, a grooved side rail consisting of two metal channel strips which are nested together, and a cushioning strip which is positioned about the back and sides of the outer metal strip with its edges clamped between the sides of the outer metal strip and the sides of the inner metal strip.
- 25 2. In a sash, a grooved side rail consisting of two sheet metal channel strips which are nested together, and a cushioning strip which is positioned about the back and sides of the outer metal strip with its edges clamped between the sides of the outer metal strip and the sides of the inner metal strip, the inner metal strip being provided

beyond the edges of the outer metal strip with outturned flanges.

3. In a sash, the combination with a pane of glass, and top and bottom rails on the upper and lower edges of the glass, of metal side rails of outwardly flanged U-shaped cross section into which the ends of the top and bottom rails and the side edges of the glass project.

4. In a sash, the combination with a pane of glass, and top and bottom rails on the upper 10 and lower edges of the glass, of sheet metal side rails of outwardly flanged U-shaped cross section into which the ends of the top and bottom rails and the side edges of the glass project, and fabric covered sheet metal bearing strips of 15 U-shaped cross section fitted over the side rails in tightly engaged reinforcing relation thereto.

5. In a sash, the combination with a pane of glass, and top and bottom rails on the upper and lower edges of the glass, of metal side rails of 20 U-shaped cross section and rubber glazing strips on the edges of the glass, said glazing strips being positioned in grooves provided in all of the rails, and said side rails extending the full height of the sash beyond the upper and lower ends of 25 the glazing strips on the side edges of the glass in the side rails, with the ends of the top and bottom rails projecting into and secured to the bottoms of the grooves in the side rails immediately above and below the ends of the glazing 30 strips in the side rails.

CHRISTIAN M. VERHAGEN.
